UNITED STATES PATENT OFFICE.

FREDERICK J. TROLL, OF BALTIMORE, MARYLAND.

CONNECTOR FOR ELECTRICAL CONDUCTORS.

No. 813,588.

Specification of Letters Patent.

Patented Feb. 27, 1906.

Application filed April 3, 1905. Serial No. 253,390.

To all whom it may concern:

Be it known that I, FREDERICK J. TROLL, a citizen of the United States, residing at Baltimore, in the State of Maryland, have invented 5 new and useful Improvements in Connectors for Electrical Conductors, of which the following is a specification.

This invention relates to connectors for electrical conductors.

10 It has for its object to improve that type of connectors which is formed by two parallel sleeves, preferably made of copper or other soft conducting material and adapted to receive the ends of two wires or conductors to be connected, the connector and the wires being twisted together.

In this type of connector the workman strips the insulating material from the inclosed conductor with a knife, and in most if 20 not all instances the soft conductor is cut or injured by the knife at the point where the conductor leaves the insulation. The conductor, on being fitted into the sleeve until the ends of the insulation engage the ends of 25 the sleeve, brings the injured part of the conductor to a position where no support is provided for it. If the two connected conductors are subjected to much handling, the conductors will very soon break at this point, 30 making a new connection and a new connector necessary.

In my invention I provide enlarged extensions at each end of the connector adapted to receive a portion of the insulation on 35 each conductor. The enlarged extensions are of soft material, which permits of their being clamped upon the insulation and thereby forming an additional securing means for the wires. Further, they are so disposed that the 40 conductors lead from the connector in alignment with one another.

Other objects and advantages will appear from the following description and will be more particularly pointed out in the appended claims.

45 In the drawings, Figure 1 is an enlarged plan view of one embodiment of my invention. Fig. 2 is a horizontal section of the embodiment shown in Fig. 1. Fig. 3 is a side elevation. Fig. 4 is a plan of the same embodiment with conductors fitted therein; and Figs. 5, 6, and 7 are respectively a plan, a horizontal section, and a side elevation, of another embodiment of my invention.

55 Referring more particularly to the drawings, 1 and 2 indicate a pair of connected par-

allel conductor-sleeves made of soft copper or other conducting material.

In the embodiment shown in Figs. 1 to 3 each conductor-sleeve has integral with and 60 extending from one end thereof, but at opposite ends of the conductor, an enlarged insulation-sleeve 3, which is of soft metal adapted to be clamped on the insulation to provide an additional securing means for the 65 conductor. The sleeves 3 are so deflected that the conductors 4 lead from them at a point midway between the two conductor-sleeves 1 and 2, thereby causing the conductor-wires to lead from the connector in alignment with one another. 70

In the embodiment shown in Figs. 4 and 5 the conductor-sleeves 1 and 2 are of known form and the enlarged insulation-sleeves 3^a are formed of separate pieces which surround 75 and are secured by solder or otherwise to the ends of both conductor-sleeves. These sleeves 3^a lead the conductors from sleeves 1 and 2 in alignment with one another, as in Figs. 1 to 3. 80

In both embodiments the insulation-sleeves are provided with slits 5, which permit of the enlargement and contraction of the sleeves to fit different-sized insulations.

The insulation-sleeves not only brace or 85 support the conductor-wires at the weak portion thereof, but they form an additional securing means for the conductors. Connectors made in accordance with my invention make the conductors as strong at the point of 90 joining as at any other point, and when once put in place do not have to be renewed, lasting as long as the conductor will last.

I desire it to be understood that within the scope of the appended claims I may make 95 various changes in the form, the proportions, and the details of construction without departing from the spirit or sacrificing any of the advantages of my invention.

Having thus described my invention, what 100 I claim, and desire to secure by Letters Patent, is—

1. In an electrical-conductor connector, a pair of connected parallel conductor-sleeves, and an enlarged insulation-sleeve at each end 105 of the pair of conductor-sleeves.

2. In an electrical-conductor connector, a pair of connected parallel conductor-sleeves, and an enlarged insulation-sleeve formed of soft metal, located at each end of the pair of 110 conductor-sleeves.

3. In an electrical conductor-connector, &

- pair of connected parallel conductor-sleeves, and enlarged insulation-sleeves at opposite ends of the conductor-sleeves, said insulation-sleeves being in alinement with one another.
- 5 4. In an electrical-conductor connector, a pair of connected parallel conductor-sleeves, and an enlarged insulation-sleeve formed of soft metal, located at each end of the pair of conductor-sleeves; said enlarged insulation-sleeves being in alinement with one another.
- 10 5. In an electrical-conductor connector, a pair of connected parallel conductor-sleeves, and a pair of insulation-sleeves, one at each end of the connector, said insulation-sleeves being disposed so that the conductor-wires lead from the connector in alinement with one another.
- 15 6. In an electrical-conductor connector, a pair of connected parallel conductor-sleeves, and a pair of insulation-sleeves one at each end of the connector, said sleeves being provided with slits.
7. In an electrical-conductor connector, a pair of connected parallel conductor-sleeves formed of soft metal to be twisted, and an enlarged insulation-sleeve at one end of the pair of conductor-sleeves.

In testimony whereof I affix my signature in presence of two subscribing witnesses.

FREDERICK J. TROLL.
